ELECTRONIC BATTERY CHARGER

Paul E. Brefka and Morris M. Knepp, Framingham,
Mass., assignors, by mesne assignments, to Tyco Laboratories, Inc., Waltham, Mass.

Filed Feb. 26, 1968, Ser. No. 10,730

Term of patent 14 years

Int. Cl. D13—02

U.S. Cl. D26—15

FIG. 1

FIG. 2

FIG. 3

FIG. 4

FIG. 5

FIG. 6

FIG. 1 is a front elevational view of the electronic battery charger;

FIG. 2 is a side elevational view;

FIG. 3 is an opposite side elevational view;

FIG. 4 is a rear elevational view;

FIG. 5 is a top plan view; and

FIG. 6 is a bottom plan view.

The dominant features of our design reside in the portions shown in full lines. The stippled area represents a covering for the electronic components contained in the chassis.

We claim:

The ornamental design for an electronic battery charger, substantially as shown and described.
